US00D632535S

(12) **United States Design Patent**
Kriz et al.

(10) **Patent No.:** **US D632,535 S**
(45) **Date of Patent:** ** *Feb. 15, 2011

(54) **ROTARY RATCHET WRENCH**

(75) Inventors: **Anthony Kriz**, Lone Tree, CO (US);
YaoKun Gui, Shanghai (CN); **Brent Christopher**, Portland, OR (US); **Mark Holtan**, Centennial, CO (US)

(73) Assignee: **Meridian International Co., Ltd. (CN)**

(**) Term: **14 Years**

(21) Appl. No.: **29/361,537**

(22) Filed: **May 12, 2010**

Related U.S. Application Data

(63) Continuation of application No. 12/617,200, filed on Nov. 12, 2009.

(51) **LOC (9) Cl.** **08-05**

(52) **U.S. Cl.** **D8/28**

(58) **Field of Classification Search** D8/17,
D8/21-29, 354, 107; 81/60, 177.1, 177.85,
81/121.1, 124.3, 165-170, 110.1, 176.2,
81/124.6, 176.1, 176.15, 177.2, 186; 16/110.1;
D15/144.1, 143; 219/75, 227, 229, 121.16,
219/121.18

See application file for complete search history.
